WALTER D. WOOD, OF ALLENTOWN, PENNSYLVANIA, ASSIGNOR TO FUEL SAVING COMPANY, OF ALLENTOWN, PENNSYLVANIA, A CORPORATION OF PENNSYLVANIA.

FIRING-CHAMBER FOR POWDERED FUEL.

1,222,344.

Specification of Letters Patent. Patented Apr. 10, 1917.

Original application filed November 11, 1915, Serial No. 60,827. Divided and this application filed June 22, 1916. Serial No. 105,121.

To all whom it may concern:

Be it known that I, WALTER D. Wood, a citizen of the United States, and resident of Allentown, in the county of Lehigh and State of Pennsylvania, have invented certain new and useful Improvements in Firing-Chambers for Powdered Fuel, of which the following is a specification, reference being had therein to the accompanying drawing.

My present invention has reference to a fire box or chamber belonging to a locomotive or boiler furnace, or any other kind of a furnace, in connection with which powdered fuel such as crushed or comminuted coal is used, and this application is a division of my former application for patent on a firing chamber for powdered fuel, filed November 11, 1915, Serial No. 60,827, the present application having particular reference to the construction of the firing chamber. The special object of the invention is to improve the construction of the fire box and also to enable the accumulations of the products of combustion such as the slag resulting from the burning of the powdered fuel and other refuse materials to be readily and easily removed from the bottom of the fire box as occasion may require. The invention, therefore, consists essentially in the construction, arrangement and combination of the various parts, substantially as will be hereinafter described and claimed.

In the accompanying drawing illustrating my invention:

Figure 1 is a vertical section of my improved firing chamber for powdered fuel on the line 1, 1 of Fig. 2;

Fig. 2 is a vertical section of the same on the line 2, 2 of Fig. 1;

Fig. 3 is a detail front view of a portion of the firing chamber together with the slag pan and a power mechanism for operating the same;

Fig. 4 is a side view of a removable central portion of one of the fire bricks used in the arch in the firing chamber;

Fig. 5 is a cross-section of said brick;

Fig. 6 is a plan view of the same;

Fig. 7 is a sectional plan view of the slag pan on the line 7, 7 of Fig. 2.

Similar characters of reference designate corresponding parts throughout the different figures of the drawing.

1 denotes the upper interior of the fire box below the boiler space 2. The walls of the fire box are usually double as shown at 3. 4 denotes the fire door. 5 denotes a group of fire tubes which run through the water space and receive the flame that heats the tubes and thereby heats the water. In the fire box 1 is an arch 6 which is inclined rearwardly and upwardly. It preferably consists of a number, say three, of supporting water tubes 7 which carry bricks seated upon them, there being a space 8 left at the rear end of the arch near the rear head of the boiler so that the flame underneath the arch will be deflected rearwardly and then upwardly through the opening 8 in the direction shown by the arrows and then over into the space above the arch, then toward and into the front group of horizontal tubes 5. The bricks which compose the arch 6 may be arranged in any desired manner. I find it convenient to employ two rows of such bricks 9, which rows are longitudinally inclined and which rest on the tubes 7, and outside of these two rows are two other rows of bricks 10 which are doubly inclined in position as shown in Fig. 2, one incline being longitudinal and the other transverse, so that the rows of bricks 10 have their inner edges resting against the walls 3 of the fire box. Some of the bricks 9 and 10 are provided with openings 11 and 12 which are preferably staggered as shown in Fig. 2 so that the arch may take the form of a semi-open arch. These openings allow the flame from the fuel to course freely into the upper part of the fire box and meet the tubes 5, and also they allow the draft created in the front end of the locomotive by the exhaust from the stack to pass directly through said openings so that a portion of the flame is drawn directly through the arch, and thus the whole area of the fire brick is utilized and combustion is increased. The staggered openings have sometimes been provided by me by leaving spaces between the bricks, but in the present case I find it more convenient to construct the bricks with the openings formed therein. One of these bricks, as 9, is shown in plan view in Fig. 6 and in section in Fig. 5, said brick having the opening 11 therein adapted to be closed if desired by the inclined plug 13 shown in Fig. 4. By providing bricks having inclined openings

and correspondingly-shaped plugs I can at any time open or close as many of the staggered openings as I may desire and thus control the passage of the flame at different points. The shape of the brick, and its opening and plug may vary as widely as desired.

The powdered fuel is introduced into the fire box through an opening 14 which receives a fuel-laden current of air propelled by some suitable blast appliance and bringing the fine fuel from a source of supply, the details of all of which need not be set forth in the present description. Directly above the opening 14 and extending for a certain distance into the fire box is a curved horizontal auxiliary arch 45, the purpose of which is to carry the stream of fuel-laden air farther forward into the firing chamber and thus distribute it more evenly, and at the same time greatly aid the combustion by reason of the additional glowing surface presented to the fuel immediately upon its entrance into the fire box. It also tends to prevent the flame from going directly through the opening 8. My improved firing chamber omits the grate, ash pan and other details usually accompanying such a chamber, and thus makes it possible for me to provide the fire box with a depressed auxiliary chamber 15 sheathed with fire bricks, the sides 16 of which chamber slope inwardly and downwardly toward the bottom 17, while the bottom 17 itself inclines forwardly and downwardly, and also the ends 18 of the depressed auxiliary chamber 13 like the sides 16 slope inwardly and downwardly to the sloping bottom 17; of course, these inclinations may be reversed or changed as desired, being governed by the construction of the furnace.

At some suitable point in the bottom, preferably near the front end, or wherever it may be best to locate it in order that the flow thereof into the chamber 15 may take place with ease and accuracy, I form an opening 19 beneath which I locate a slag pan 20. Immediately below the opening 19, said opening is surrounded by a passage, nozzle, or pipe 21, which is secured to the underside of the bottom 17 in such a manner that it will encircle the opening 19 and will project downwardly below the bottom 17 for a certain distance. The slag pan 20 is made in two sections 22, which together form an oblong or other suitably-shaped box, said sections being pivotally supported at their upper ends so that they may swing toward and away from each other. When they swing toward each other, their edges meet, and thus the slag pan 20 is closed. When they swing away from each other, the pan opens so that its contents will discharge. This slag pan receives from the firing chamber through the bottom opening 19 any slag or other foreign matter that may form in the

process of combustion, since said matter will work to the lowest point in the bottom of the chamber and will drop through said opening and be caught by the slag pan. The pivoting of the upper edges of the sections 22 is preferably accomplished by means of rods 23 carried in bearings on the outside of the discharge pipe 21, as shown in Figs. 1 and 2, at a point slightly above the bottom edge of said pipe 21 so that said pipe may discharge its contents into the pan without causing them to come into contact at all with the pivotal hinge or joint at the upper edge of the section 22. It is furthermore to be particularly noted with reference to the shape and construction of the sections 22 that their vertical sides 24 are inwardly inclined from bottom to top, while their bottom portions 25 are inwardly and downwardly inclined from the outside walls 24 to the meeting edges of said bottom parts 25, and that the end walls (see Fig. 7) are inclined from the sides 24 to the meeting edges of parts 22 so as to prevent the slag from accumulating in the corners of the pan and to make it easier for the pan contents to be discharged and render it impossible for the slag to adhere to the parts and thus prevent opening.

The rods 23 which are rigidly attached to the sections 22 of the dumping pan 20 and are movably supported in bearings on the discharge spout 21, as already explained, extend a short distance away from the spout and are supported by bearings 26. The ends of the rods 23 are provided with rigid crank arms 27 which are pivoted to links 28 that are likewise pivoted to the lower end of a piston rod 29 attached to a piston within a power cylinder 30 receiving steam or air pressure through pipes 31 from some suitable supply for the purpose of actuating the piston and thus operating the specified system of leverage for the purpose of opening and closing the sections 22 of the slag pan so as to dump the contents of the same. The control of the pressure in pipes 31 is manipulated from the cab or otherwise. I have indicated this power cylinder simply as one means for furnishing a device of sufficient strength to actuate the parts of the slag pan in dumping and closing the latter, but without any intention of being restricted to the use of a cylinder and piston, inasmuch as various other means can be utilized with equal benefit for the same purpose, and I, therefore, reserve the liberty of opening and closing the sections of the slag pan by any suitable mechanical or other power which may be applied in any way desired.

Below the slag pan 20 is a receptacle 32 with an open top into which the slag pan dumps when its hinged sections unclose. This receptacle 32 is supported from the bottom of the firing chamber in any suitable way, as for instance, by means of the

- hangers 33 attached to the firing chamber, and also to the receptacle 32. Receptacle 32 is provided with a movable cover 34 which covers and uncovers an open part of the receptacle. When the receptacle is built with an inclined bottom, as shown in Fig. 2, this cover 34 will be arranged in connection with the open side of the receptacle and is provided with a lip 45 adapted to overlap the edge of the open side. This cover 34 is supported on a rod 35 held in bearings in the wall of the receptacle 32, and said rod 35 is provided with a crank arm 36 to which is pivoted a link 37 that is likewise pivoted to a bell-crank lever 38 fulcrumed at 46 at some suitable part of the main frame of the firing chamber. Bell-crank 38 is operated by a rod 39 having a handle 43 and projecting through the floor 40 of the locomotive cab or any other operating platform, on which platform 40 is a standard 41 to which the operating lever 39 may be connected by means of a pin 42. By removing the said pin 42 and setting free the operating handle, the engineer or fireman can by laying hold of the handle 43 actuate the bell-crank 38 and open the cover 34 of the receptacle 32 so that its contents will be readily discharged.
- 30 Many changes may be made in the construction and arrangement of the various parts without exceeding the scope of the invention, and I reserve the liberty of changing the operative details as much as may be necessary in carrying the invention into actual practice.
- Having thus described my invention, what I claim as new and desire to secure by Letters Patent, is:
- 40 1. The combination of a firing chamber having an inlet for receiving the fuel laden vehicle, a horizontally-projecting auxiliary arch directly above the inlet for the purpose of carrying the fuel into the firing chamber for a certain distance beyond the inlet, an inclined arch having a rear opening which is
- located above said auxiliary arch, said inclined arch being composed of water tubes and a series of bricks supported thereon, and said arch being provided at intervals with transverse openings to allow the flame to pass through the arch at certain points, together with plugs adapted to be placed in said openings to enable them to be staggered or otherwise related as desired. 55
2. The combination of a firing chamber having an inlet for receiving the fuel-laden vehicle, a horizontally projecting auxiliary arch directly above the inlet for the purpose of carrying the fuel into the firing chamber for a certain distance, and an inclined arch having a rear opening which is located above said auxiliary arch, said inclined arch being composed of water tubes and series of bricks supported thereon, said bricks being provided with central openings in order that the arch may thus furnish transverse passages for the flame, and plugs for said openings to enable the openings to be staggered or otherwise related as desired. 60
3. The combination with a firing chamber having a lepressed auxiliary chamber provided with an inlet opening for receiving a stream of powdered fuel, of a horizontally projecting transversely curved arch 75 at the top of said inlet for guiding the stream of fuel into the firing chamber for a short distance beyond the inlet, and an inclined arch in the firing chamber composed of inclined tubes and series of bricks supported thereon, some of said bricks being formed with central inclined apertures so that the arch may provide transverse passages at certain points for the discharge of the flame, together with inclined plugs 80 adapted to be placed in said apertures so that some will be closed and others opened as desired. 85

In testimony whereof I hereunto affix my signature.

WALTER D. WOOD.
